CLAIM

The ornamental design for a siding trim piece, as shown and described.

DESCRIPTION

FIG. 1 is a top and front perspective view of a trim piece showing my new design;

FIG. 2 is a bottom and front perspective view of the trim piece of FIG. 1;

FIG. 3 is a bottom and rear perspective view of the trim piece of FIG. 1;

FIG. 4 is a top and rear perspective view of the trim piece of FIG. 1;

FIG. 5 is a front view of the trim piece of FIG. 1;

FIG. 6 is a back view of the trim piece of FIG. 1;

FIG. 7 is a top view of the trim piece of FIG. 1;

FIG. 8 is a left view of the trim piece of FIG. 1;

FIG. 9 is a right view of the trim piece of FIG. 1; and,

FIG. 10 is a bottom view of the trim piece of FIG. 1.

The claimed design is broken in the center to indicate indeterminate length.
